KEY READILY REMOVABLE FROM AND
REPLACEABLE ONTO A KEY RING

Theodore Hewitt Johnstone, Detroit, Mich.

Application July 13, 1950, Serial No. 173,659

10 Claims. (Cl. 70—408)

1

This invention relates to keys adapted to be readily removed from and placed on to a key ring or other key retainer.

Readily removable and replaceable keys heretofore known have, among others, the objections they can only be made from special blanks and they require spring pressed locking mechanisms, such as the well known jewelry safety catches. For these reasons the heretofore known keys of this type have been relatively costly to manufacture and have met with little or no commercial favor.

It is among the objects of this invention to provide keys which are adapted to be readily removed from and placed on to key rings, which keys can be made from standard key blanks, such as the well known Yale, Sargent, Russwin, Corbin and other blanks now available, which are simple and rugged in design, which are inexpensive to manufacture and which are efficient in use in that they can readily and conveniently be removed from and replaced onto a key ring.

Other objects and advantages of this invention will be apparent from the following detailed description thereof.

In accordance with this invention an opening is formed in the key head, the opening leading into the periphery of the head. Disposed in one side of the head is a groove or channel which leads into the opening. A locking member, desirably of spring metal, is slidably mounted in this channel and is adapted to be moved to bridge the opening and thus close it to prevent removal of the key from the ring. The locking member may also be moved in a direction to retract it within its channel, thus opening said opening and permitting the ready removal of the key from the key ring. A cam member on the locking member cooperates with the walls of the opening and of the channel to place the locking member under tension when it is retracted within the channel, which tension is released when the locking member is moved in a direction to bridge the opening causing the locking member to snap in place with the cam member in locking engagement with the sides of the opening to firmly close the opening.

In the preferred embodiments illustrated on the drawing the invention is shown incorporated in keys having substantially circular heads and the present description will be confined to the present illustrated embodiments of the invention. It will be understood, however, that the novel features and improvements are susceptible to other applications, such as keys having other

2

shaped heads including conventional key blanks, such as the Sargent, Yale, Russwin, Corbin, etc., blanks now available. Hence, the scope of this invention is not confined to the embodiment herein described.

In the accompanying drawing,

Figure 1 is a plan view of a key head embodying this invention showing the locking member in closed position;

10 Figure 2 is a plan view with parts broken away to show the interior structure and showing the locking member in open position to permit the ready removal of the key from a key ring;

Figure 3 is a vertical section taken in a plane passing through line 3—3 of Figure 1;

Figure 4 is a vertical section taken in a plane passing through line 4—4 of Figure 1;

Figure 5 is a composite perspective view showing a key head as formed prior to the insertion 20 of the locking member therein, the locking member and the cap, which parts when assembled form the construction of Figures 1 to 4, inclusive;

Figure 6 is a plan view of a key head on a somewhat reduced scale as compared with the 25 scale of Figures 1 and 2 and showing a modified form of this invention;

Figure 7 is a vertical section taken in a plane passing through line 7—7 of Figure 6; and

Figure 8 is a perspective view of the cap employed in producing the key of Figures 6 and 7.

30 In the drawing 10 indicates the head of a key provided with a bit 11 which is shown fragmentarily. The head, as customary, has a peripheral edge 12 and opposite sides 13 and 14. An opening 15 is formed in the head of the key, preferably by stamping, this opening leading from the peripheral edge 12 towards the interior of the head of the key. In the construction shown in the drawing the opening is defined by side walls 16 and 17 leading from the periphery 12 into a rounded lower edge portion 18. An arcuate groove or channel 19 is formed in the head of the key leading from one side wall 16 of the opening 15 to the opposite side wall 17, as shown 35 in Figures 1 and 2.

40 Disposed in this arcuate groove or channel is a locking member 20 desirably of the shape shown in Figure 5. This locking member is of spring metal, e. g., steel, and comprises a flat arcuate portion having rounded ends 21, 22. 45 Disposed near end 22 is a cam member 23 which is formed on the periphery of the locking member 20 and has the forward edge 24 shaped so that it provides an abutment, the function of which 50 will be hereinafter described. The rear edge of

this cam member is inclined as indicated at 25. The length of the cam member 23 is equal to the width of the opening 15 so that when the locking member is in place to close this opening, abutment 24 abuts against side 17 of the opening 15 and the inclined portion 25 of this cam member is disposed within opening 15 close to side wall 16, as shown in Figure 1.

Locking member 20 has thereon a raised portion 26 desirably disposed diametrically opposite the cam member 23. The face of this raised portion is roughened or serrated, as at 27, to facilitate engagement of the raised portion to effect movement of the locking member 20 in the groove or channel 19.

Locking member 20 is maintained under tension in groove or channel 19, the peripheral edges of the relatively wide portion 28 of this locking member being in frictional contact with the side edges of the portion of channel 19 in which wide portion 28 moves. Also the cam member 23, when the locking member is in the retracted position shown in Figure 2, frictionally engages the vertical wall 29 of channel 19. A flange 30 integral with side 13 extends over the top of channel 19 and acts as a retaining wall to maintain the locking member 20 in place for sliding movement within this channel, preventing accidental displacement of this locking member.

A cap 31 is desirably positioned, as shown in Figures 1 and 2, to cover the major portion of the locking member. This cap has an interior circular flange 32, peripheral flanges 33, 34 separated to provide the space 35, and an opening 36 adapted to register with opening 15. When the cap is in position, space 35 provides a narrow arcuate slot 37 through which raised portion 26 extends and which slot permits movement of the raised portion 26 from the position shown in Figure 2 to that shown in Figure 1 and back. The ends of flanges 33 and 34 act as stops to limit movement of raised portion 26 in arcuate slot 37. In the structure of Figure 1 the cap improves the appearance of the key; also it affords a convenient place for applying a trademark or other suitable indicia.

In fabricating the key embodying this invention, it is only necessary to stamp out the opening 15 in the head of the key blank. This blank may be any well known type of available blank. Simultaneously or successively the side 13 of the head is milled to form the channel 19 having the integral flange 30 and the arcuate grooves 37 and 38 forming an upstanding arcuate rib 39, a central button or raised portion 40 and an arcuate portion 41, the edge 42 of which defines a side wall of channel 19. Locking member 20 is then disposed in channel 19. Thereafter cap 31 is placed in position with the opening 36 registering with opening 15, flange 32 disposed in the arcuate groove 38, the edges of flanges 33 and 34 in abutment with the marginal edge of flange 30 and the raised portion 26 extending through the arcuate slot 37. Rib 39 is then flattened by a suitable tool to the position shown in Figure 4 to fasten the cap in place.

In operation when it is desired to remove a key from a key ring, it is only necessary to engage raised portion 26 and move it from the position shown in Figure 1 to that shown in Figure 2. Such movement causes the inclined portion 25 of cam member 23 to engage the inner edge of channel 19 causing the locking member to be placed under tension with the cam member in frictional contact with the wall 29 of channel 19. 75

Opening 15 in the key head is thus opened and the key can readily be removed from the key ring.

When it is desired to replace the key on a key ring, it is moved so that the key ring passes through opening 15. Raised portion 26 is then moved through arcuate slot 37 in the opposite direction. As the cam member begins to ride free of wall 29, and 22 enters the channel opening leading into side wall 17 and in the continued movement of the locking member the cam member thereon snaps out with the abutment wall 24 engaging wall 17 providing a firm and positive closure for opening 15.

The modification of Figures 6, 7 and 8 differs 15 from that of Figures 1 to 5 chiefly in that the locking member 20 is retained in channel 19 by the cap member 31. In the modification of Figures 6, 7 and 8 side 13 of the head is not provided with a flange corresponding to flange 30, but the flanges 34 and 33 of the cap abut the side wall 43 of the channel 19. The flanges 33 and 34 are in frictional contact with the face of the locking member 20 and maintain it within the channel 19. The cap 31 is retained in place not only by the rib 39 locking with flange 32 of the cap, as shown in Figure 6, but also by a pair of ears 44 and 45 which are bent to engage the side walls 16 and 17 of opening 15.

The operation of the modification of Figures 6 and 7 is substantially the same as that of the other modification and should be clear from the above description of the operation of the other modification.

It will be noted the key of this invention can 35 readily be fabricated from standard key blanks. The fabrication requires a simple stamping and milling operation which is relatively inexpensive. The locking member can readily be stamped to shape from spring metal. The cap also, if used, can be stamped to shape. The parts can readily be assembled to produce the finished product which is substantially less costly to manufacture than readily removable and replaceable keys heretofore known. The resultant key, it will be further noted is simple and rugged in design and is efficient in use in that it can readily and conveniently be removed from and replaced onto a key ring.

The term "key ring" is used herein in a broad 50 sense to include any and all key retainers whether of true ring or other shapes. The term "side" is used in a broad sense and includes the face as well as the back of a key head.

Since certain changes may be made in the 55 above article and different embodiments of the invention could be made without departing from the scope thereof, it is intended that all matter contained in the above description or shown in the accompanying drawing shall be interpreted as illustrative and not in a limiting sense.

What is claimed is:

1. A key adapted to be readily removed from and placed onto a key ring comprising a head having an opening leading into the periphery thereof and a channel in one side of the head extending from one wall of said opening in a direction away from said opening, a locking member slidably mounted in said channel and adapted to be moved to bridge said opening and close same to prevent removal of the key from a key ring and also to be moved in a direction to open said opening so that said key can readily be removed from the key ring, and a cam member on said locking member said cam member being

dimensioned to bridge said opening and abut the walls thereof to lock said locking member in place, said locking member being tensioned to cause said cam member to snap into said opening upon movement of said locking member to position the cam member in said opening.

2. A key adapted to be readily removed from and placed onto a key ring comprising a head having an opening leading into the periphery thereof and a channel in one side of the head extending from one wall of said opening in a direction away from said opening, a spring metal locking member slidably mounted in said channel and adapted to be moved to bridge said opening and close same to prevent removal of the key from a key ring and also to be moved in a direction to open said opening so that said key can readily be removed from the key ring, and a cam on the periphery of said locking member near one end thereof, said cam cooperating with the terminal end of said channel so that when said locking member is moved in a direction to open said opening the locking member is placed under tension and is maintained under tension within said channel and when moved in the opposite direction to bridge said opening and close same, said tension is relieved and the locking member snaps in place to bridge said opening with the cam abutting the walls of said opening to lock said locking member in place bridging said opening.

3. A key adapted to be readily removed from and placed onto a key ring comprising a head having an opening extending from the periphery of said head into the interior portion thereof, a channel in one side of said head extending from one side wall of the opening, and a metal arcuate locking member disposed in said channel for sliding movement therein, said locking member having a cam member on one peripheral edge thereof and a raised portion adapted to be engaged to effect movement of said locking member in said channel, said cam member being dimensioned to abut the walls of said opening to lock said locking member in place bridging said opening, said locking member being tensioned to cause said cam member to snap into said opening upon movement of said locking member to position the cam member in said opening.

4. A key adapted to be readily removed from and placed onto a key ring comprising a head having an opening extending from the periphery thereof towards the interior of the head and having in the side of the head an arcuate channel extending from one side wall of said opening into the opposite side wall of said opening, a metal arcuate locking member disposed in said channel for sliding movement therein, said locking member having a cam member on its periphery near one end thereof and having a raised portion extending above the surface of the side of the head in which said channel is disposed, said cam member being dimensioned to abut the side walls of said opening to lock said locking member in place with the cam member bridging said opening, said raised portion adapted to be engaged to effect movement of said locking member in said channel to bridge said opening and close same to prevent removal of a key from a key ring and also to be moved in a direction to open said opening so that said key can readily be removed from the key ring, said locking member being tensioned to cause said cam member to snap into said opening upon movement of

said locking member to position the cam member in said opening.

5. A key adapted to be readily removed from and placed onto a key ring comprising a head having an opening extending from the periphery thereof towards the interior of said head, one side of said head having therein an arcuate channel extending from one side wall of said opening into the other side wall thereof, a metal arcuate locking member disposed in said channel for sliding movement therein, a flange integral with the side of said head in which said channel is disposed for retaining said locking member in position in said channel, said locking member having a cam member on a peripheral edge thereof near one end of the locking member and having a raised portion extending through said channel above the surface of said side of said head so that said raised portion can readily be engaged to effect movement of said locking member in said channel in a direction to bridge said opening and close same to prevent removal of the key from a key ring and also in the opposite direction to open said opening so that said key can readily be removed from the key ring, said cam member being dimensioned to abut the side walls of said opening to lock said locking member in place with the cam member bridging said opening, said locking member being tensioned to cause said cam member to snap into said opening upon movement of said locking member to position the cam member in said opening.

6. A key adapted to be readily removed from and placed onto a key ring comprising a head having an opening extending from the periphery thereof towards the interior of said head, one side of said head having therein an arcuate channel extending from one side wall of said opening into the other side wall thereof, a metal arcuate locking member disposed in said channel for sliding movement therein, said locking member having a cam member on a peripheral edge thereof near one end of the locking member and having a raised portion extending through said channel above the surface of said side of said head so that said raised portion can readily be engaged to effect movement of said locking member in said channel in a direction to bridge said opening and close same to prevent removal of the key from a key ring and also in the opposite direction to open said opening so that said key can readily be removed from the key ring, and a cap covering said channel except for a narrow portion through which narrow portion said raised portion extends, said cam member being dimensioned to abut the side walls of said opening to lock said locking member in place with the cam member bridging said opening, said locking member being tensioned to cause said cam member to snap into said opening upon movement of said locking member to position the cam member in said opening.

7. A key adapted to be readily removed from and placed onto a key ring comprising a head having an opening extending from the periphery thereof towards the interior of said head, one side of said head having an arcuate channel therein extending from one side wall of said opening into the other side wall thereof, a metal arcuate locking member disposed in said channel for sliding movement therein, a flange integral with the side of said head in which said channel is disposed and overhanging said channel for retaining said locking member in said channel, said locking member having a cam member on a

peripheral edge thereof near one end of said locking member and having a raised portion extending through said channel above the surface of said side of said head containing said arcuate channel so that said raised portion can readily be engaged to effect movement of said locking member in said channel in a direction to bridge said opening and close the same to prevent removal of the key from the key ring and also in the opposite direction to open said opening so that said key can readily be removed from the key ring, said cam member being dimensioned to abut the side walls of said opening to lock said locking member in place with the cam member bridging said opening, said locking member being tensioned to cause said cam member to snap into said opening upon movement of said locking member to position the cam member in said opening, and a cap covering said channel except for a narrow portion through which narrow portion said raised portion extends, said cap having ears engaging the walls of said opening and preventing movement of said cap upon movement of said locking member in said channel.

8. A key adapted to be readily removed from and placed on to a key ring comprising a head having an opening extending from the periphery thereof towards the interior of said head, one side of said head having an arcuate channel therein extending from one side wall of said opening in a direction away from said opening, an arcuate locking member disposed in said channel for sliding movement therein, said locking member having a cam member on a peripheral edge thereof near one end of said locking member and having a raised portion extending through said channel above the surface of said side of said head containing said arcuate channel so that said raised portion can readily be engaged to effect movement of said locking member in said channel in a direction to bridge said opening and close the same to prevent removal of the key from the key ring and also in the opposite direction to open said opening so that said key can readily be removed from the key ring, said locking member being tensioned to cause said cam member to

8
snap into said opening upon movement of said locking member to position the cam member in said opening.

9. A key as defined in claim 8, in which the arcuate locking member is in the form of a relatively flat narrow arcuate member with the raised portion and the cam member substantially diametrically opposite each other and with the raised portion extending from one peripheral edge of said member substantially perpendicular thereto.

10. A key adapted to be readily removed from and placed on to a key ring, said key comprising a head having an opening extending from the periphery thereof towards the interior of said head, one side of said head having an arcuate channel therein extending from one side wall of said opening in a direction away from said opening, an arcuate locking member disposed in said channel for sliding movement therein, said locking member having a cam member on a peripheral edge thereof and having a raised portion extending through said channel above the surface of said side of said head containing said arcuate channel so that said raised portion can readily be engaged to effect movement of said locking member in said channel in a direction to bridge said opening with the cam member disposed in said opening to close the same to prevent removal of the key from the key ring and also in the opposite direction to open said opening so that said key can readily be removed from the key ring.
